CLOTH TAKE-UP MECHANISM FOR LOOMS

James M. Tuten, Greenville, S. C., assignor to
Draper Corporation, Hopedale, Mass., a corpora-
tion of Maine

Application March 21, 1947, Serial No. 736,238

5 Claims. (Cl. 139—308)

1

This invention relates to cloth take-up mechanisms for looms, and more particularly to improved means for guiding and actuating the mechanism which supports the cloth roll of such mechanisms.

In a commonly used form of loom the cloth is drawn from the weaving line by a positively driven take-up roll and is wound upon a cloth roll which is rotated through frictional contact with the take-up roll at the bottom of the latter. The cloth roll is supported at its ends in saddles formed in the upper ends of gear rack members which are stressed upwardly to keep the cloth roll in contact with the take-up roll. The gear rack members are supported and guided for up and down movement by guideways formed in respective upright stands mounted on a front girt of the loom. The gear racks are stressed to raise the cloth roll into contact with the take-up roll through the action of pinions meshing with the racks and secured on a shaft carried in bearings formed in the upright stands, which shaft is placed under proper torsional stress by adjustable mechanism including a torsion spring. The arrangement is such that as the cloth is wound on the cloth roll and the cloth mass increases in diameter the racks are forced downwardly, rotating the pinions and shaft, and further tensioning the torsion spring. As commonly constructed each upright stand has formed thereon a gear rack guide lug for guiding the lower portion of the gear rack and for maintaining the rack in mesh with its respective pinion.

Due to constant vibration of the loom during weaving and to other causes, the pinion and gear rack teeth are subject to relatively rapid wear, as is the gear rack guide lug. Such wear has necessitated frequent replacement of the affected parts, and is the source of considerable expense due to defective operation caused by faulty meshing of the racks and pinions and to the consequent lost loom operating time. Efforts have been made to overcome the troubles mentioned, and have included forming the rack with unusually long teeth, the application of shims to the guide lug to force the gear rack into engagement with its pinion, and the application to the stand of an adjustable guide lug. Neither of these solutions has proved to be wholly satisfactory. Increasing the rack tooth length required the employment of shims or the like on the guide lug, which forced the rack out of proper alignment with its guideways. The same defective action resulted from employment of an adjustable rack guide lug.

2

With the aforementioned defects of prior cloth take-up mechanisms in mind, it is an object of the present invention to provide a cloth take-up mechanism of the type above described including means permitting adjustment of both the rack guide lug and the rack pinion toward and away from the gear rack, whereby wear of those parts may be compensated without moving the gear rack out of alignment with its guideways.

10 It is another object of the invention to provide a cloth roll stand unit including a stand, a pinion shaft bearing, a rack guide lug, and means common to those three elements adjustably securing the pinion shaft bearing and rack guide lug to the stand. Another object of the invention is to provide general improvements in cloth take-up mechanisms of the type mentioned.

The above objects, and other objects which shall appear hereinafter, are attained by structure according to the present invention. One preferred embodiment of such structure illustrating the invention is fully disclosed in the following specification considered in connection with the accompanying drawings, wherein

15 Fig. 1 is a front view in elevation of a loom with parts removed, and equipped with structure according to the invention;

20 Fig. 2 is an isometric view of certain structure shown in Fig. 1 and showing in detail the relationship of certain parts of said structure;

25 Fig. 3 is a partial sectional view in elevation of structure shown in Figs. 1 and 2 as viewed from between the loomsides;

30 Fig. 4 is a sectional view taken on line 4—4 of Fig. 3, viewed in the direction indicated by the arrows; and

35 Fig. 5 is a view of parts according to the invention arranged in "exploded" relationship.

Referring to the drawings and more particularly to Fig. 1, there are shown two loomsides 10, 11, which are interconnected by breastbeam 12 and a front girt 13 to form a portion of a loom frame. Journalized in bearings (not shown) carried by the breast beam, and disposed to the rear of and below the breast beam, is a take up roll 14. The take-up roll is arranged to be positively driven by gearing (not shown) to draw the cloth forwardly from the weaving line and transfer it to a cloth roll 15. The cloth roll comprises a shaft 16 seated at its ends in saddles formed in the upper ends of gear racks 16, 17 which are guided for up and down movements in respective upright stands 18, 19. The stands are fixedly mounted on and secured to front girt 13 by suitable means as by bolts. Disposed trans-

versely of the stands is a spring shaft 20 carrying at each end and fixed thereto a pinion engaged with a respective one of the gear racks 16, 17. Spring shaft 20 is adapted to be yieldingly rotated in such direction as to cause elevation of the gear racks and the cloth roll by a torsion spring 21 secured at one of its ends to the shaft by suitable means, as by a collar. The spring is tensioned to cause the mentioned rotation by having its other end secured to a worm wheel 23 10 having its other end secured to a worm 24 mounted in a gear case 25 and adapted to be rotated by an articulated crank 26. The arrangement of the parts is such that when worm 24 is rotated 15 in the proper direction, worm wheel 23 rotates to tension spring 21, which, when sufficiently tensioned, rotates shaft 20 and through the pinions on the shaft elevates the gear racks to raise the cloth roll into engagement with the take-up 20 roll. The hereinabove enumerated structure generally, and its arrangement and operation, are well known to those skilled in the art to which the present invention is directed, and need no further explanation. The two upright 25 stands 18, 19, and the structures closely associated therewith, are of similar construction but of generally opposite hand at the opposite sides of the loom. The pinions fixedly carried on shaft 20 may be of identical construction. Heretofore 30 each end of shaft 20 has been supported for rotation in a bearing hole formed in a portion of the adjacent stand. As a consequence the axis of the pinions was fixed and better meshing of worn pinions and worn gear racks could be obtained only by forcing the gear racks toward respective pinions and out of natural alignment with the guideways formed in the respective stands. According to the invention means are provided which permit moving the pinions toward the respective gear racks, and which have other novel features as will be hereinafter pointed out.

In view of the similarity of the structures comprising the stands, racks and pinions, one of 45 which structures is at each end of spring shaft 20, only that one of the structures at the left hand side of the loom will be described in detail. It should be kept in mind that a similar structure of generally opposite hand is located at the opposite side of the loom, as illustrated in Fig. 1.

Referring now to Figs. 2, 3 and 4, stand 19 is formed with a generally upwardly extending slot-like opening 27 bounded by offset separated portions 28, 29. This opening acts as a guideway for gear rack 17 as may be conventional. Gear rack 17 is arranged for meshing engagement with pinion 30 fixedly secured to spring shaft 20 in any conventional manner, as by set screws. (See Figs. 3 and 4.) In attaining the objects of the invention shaft 20 is journaled in an adjustable bearing 31. The bearing comprises an integral mounting flange 32 provided with elongate holes 33 (Fig. 5) for a purpose to be explained more fully hereinafter. Further, there is provided a replaceable and adjustable gear rack guide lug, 34, having an elongate hole 35 therein and an offset rack guiding arm 36. Stand 19 is provided with two holes 37, 38, spaced as are holes 33 in bearing 31, for the reception of bolts 39, 40. Bolt 39 and its associated washer and nut form means common to the stand, the guide lug and the bearing, for securing the latter two parts to the stand. In view of the elongate nature of hole 35 stand, in view of the elongate nature of hole 35 in lug 34 and of holes 33 in bearing 31, those two 75

elements are individually adjustable forwardly and rearwardly on the stand 19. Thus shaft 20 and pinion 30 may be adjusted into proper meshing engagement with rack 17, guide lug 34 moved into guiding engagement with the rack, and bolt 39 tightened, insuring proper meshing of the gearing without moving the gear rack out of proper alignment with the guideway 27 in stand 19. The teeth of the gear rack may be formed of unusual length so when they are worn pinion 30 may be moved closer to the rack to compensate the wear. As guide lug 34 wears it may occasionally be adjusted into snug engagement with the rack. Bearing 31 may optionally be provided with a lubricant well 41 and plug 42; and a second bolt 40 is preferably passed through holes 33 and 33 and secured with a nut to more rigidly mount the bearing on stand 19. Since similar adjustable structures are provided at the two stands 18, 19, it is evident that both pinions (that at stand 18 being not shown) may be adjusted to properly mesh with a respective rack, and that each rack may be maintained in meshing engagement with a respective pinion and yet be retained in proper alignment with the respective guideway by action of an associated guide lug; and that adjustment whenever dictated by wearing of the parts will maintain these parts in their correct relationships, each to the other. Thus the bending and cramping of the racks in their guideways and other defects of the above mentioned prior art structures and expedients are avoided.

Having described a preferred embodiment of the invention it will be evident that changes and modifications within the true scope of the invention will occur to those skilled in the art, and what I claim and wish to secure by Letters Patent is:

1. In a cloth take-up mechanism for looms, a pair of generally upright stands, an individual gear rack for and slidably mounted in guideways in each stand and supporting a respective end of the cloth roll, a shaft extending generally between the stands, a pair of pinions on said shaft each at a respective gear rack, means to rotate said shaft, and individual unitary adjustable means at each of said stands acting to support said shaft and to adjustably position each of said pinions in engagement with a respective one of said racks and positioning said racks in alignment with respective ones of said guideways.
2. In a cloth take-up mechanism for looms, a cloth roll, an individual gear rack for and at each end of the cloth roll and arranged to support the latter, an individual stationary stand at and guiding each respective rack, a shaft extending transversely of the stands, pinions on said shaft each geared with a respective one of said racks, individual adjustable bearing means for and at each end of said shaft, an individual adjustable guide for each of said racks, common means at each of said stands adjustably securing a respective rack guide and a respective bearing means to a respective stand to position said pinions each in proper engagement with a respective rack and to position said racks with respect to said stands, and means to rotate said shaft.
3. In a cloth take-up mechanism for looms, a pair of spaced-apart generally upright stands each provided with a generally upwardly extending guideway; an individual gear rack for and mounted in each guideway; a cloth roll extending between said upright stands and supported by said racks; a shaft disposed transversely of said stands and extending generally therebetween;

pinions fixedly mounted on said shaft one for each gear rack; an individual bearing for and at each end of said shaft; an individual adjustable rack guide for each rack; and means at each of said stands common to a respective rack guide, stand, and bearing adjustably securing the respective rack guide and bearing to the stand and maintaining the respective pinion properly engaged with its rack and the respective rack properly aligned with its guideway; and means including a torsion spring for yieldingly rotating said shaft to raise said racks and cloth roll.

4. A cloth roll stand unit for a cloth take-up mechanism for looms, said unit comprising a cloth roll stand, a spring shaft bearing constructed and arranged to be adjustably secured on one side of said stand, a gear rack guide constructed and arranged to be adjustably mounted

on another side of said stand, and means common to and passing through said bearing, guide and stand to adjustably secure said bearing and said guide to said stand.

5. A cloth roll stand unit for looms, comprising, in combination: a generally upright stand having a rack guideway formed therein; a shaft bearing including a fastening flange; a rack guide member; and bolts each passing through apertures formed in each of said stand, bearing flange, and rack guide and securing said bearing and rack guide to said stand; said apertures in at least two of said members being elongate in a direction transverse to said stand whereby said rack guide member and said bearing member may each be individually adjusted with respect to said stand in said transverse direction.
